SHEET HOLDING DEVICE

Walter L. Wolford, Oakland, Calif.

Application March 24, 1937, Serial No. 132,862

1 Claim. (Cl. 129—18)

This invention relates to sheet holding devices and has for an object to provide a device of this character that will promote ease and rapidity of withdrawal and replenishing sheets, and will 5 promote economies in filler costs by the elimination of perforations, stapling, and the like, while at the same time will hold the sheets in presentable form for writing thereon.

A further object is to provide a device of this 10 character which will be formed of a few strong simple and durable parts, which will be inexpensive to manufacture, and which will not easily get out of order.

With the above and other objects in view 15 the invention consists of certain novel details of construction and combinations of parts herein-after fully described and claimed, it being understood that various modifications may be resorted to within the scope of the appended claim without departing from the spirit or sacrificing any of the advantages of the invention.

In the accompanying drawing forming part of this specification,

Figure 1 is a front elevation of a sheet holding 25 device constructed in accordance with the invention and showing a pad of order sheets assembled therewith.

Figure 2 is a side elevation of the parts shown in Figure 1.

Figure 3 is a cross sectional view taken on the line 3—3 of Figure 1.

Figure 4 is a detail view in elevation showing a pad of sheets particularly well adapted for use in connection with the sheet holder.

Figure 5 is a detail view in side elevation of the pad of sheets shown in Figure 4.

Referring now to the drawing in which like characters of reference designate similar parts in the various views, the sheet holder is shown 40 to comprise a substantially rectangular back plate 10 preferably formed of sheet metal and having lateral wings 11 of the general shape shown in Figure 2 bent to extend parallel with each other at opposite longitudinal edges of the 45 back plate adjacent to the top longitudinal edge of the back plate. The top of the plate is provided with a tab 12 which is bent forwardly to bridge the wings 11 at the upper edges of the wings and form a stop which butts against the upper end edges of sheets 13 assembled as a pad. The side edges of the sheets at the same time butt the wings 11 so that the sheets are held 50 assembled in a neat compact pad.

As best shown in Figure 2, slots 14 are formed

in the wings 11 at the upper end edges thereof and near the back plate 10, to produce resilient tongues 15 from which substantially semi-cylindrical ribs 16 are struck inwardly at about midway between the ends of the tongues. These ribs engage in correspondingly shaped notches 17 formed in the side edges of the sheets. The purpose of the ribbed resilient tongues is to grip the sheets and reinforce the same against accidental dislodgment under severe conditions of 50 service.

A leaf spring clamp 18 of the general shape shown in Figure 3 extends transversely across the back plate parallel with the end stop 12. One end 19 of the clamp is deformed to extend at an angle to the clamp and is clamped against the indented rib 16 of one of the spring tongues 15 by a plate 20 which extends longitudinally of the tongue and is secured at the ends to the tongue by screws 21.

The pad of sheets 13 preferably is of the type disclosed in my co-pending application filed March 15, 1937, Serial No. 131,031 and entitled Strip gum padding so that in this application it will be merely stated that strips 22 of an adhesive medium are secured to the side edges of the sheets directly opposite to each other and adjacent to the notches 17 of the sheets. These strips assemble the sheets as a unit and maintain the sheets in presentable form so that to 25 detach a sheet it is merely necessary to lift the sheet at an angle from the underlying sheets until the sheet is stripped from the adhesive medium 22 and then pull forwardly upon the detached sheet until it passes from underneath the leaf spring clamp 18.

From the above description it is thought that the construction and operation of the invention will be fully understood without further explanation.

What is claimed is:

A writing pad holder comprising a base plate, wings on the longitudinal edges of the plate forming stops for engaging the edges of a pad which may be supported on the plate, there being slots 45 formed in the wings at one end thereof adjacent to the plate to provide resilient tongues at the ends of the wings, and oppositely disposed locking ribs on the tongues adapted to be engaged in notches in the longitudinal edges of the pad for 50 yieldably retaining the pad in place on the base plate.

WALTER L. WOLFORD.
